METHOD OF RECONDITIONING BOILERS

Frank W. Miller, Chicago, Ill., assignor to
 Franclare Company, Chicago, Ill., a corpora-
 tion of Illinois

Application November 29, 1941, Serial No. 420,915

1 Claim. (Cl. 122—396)

This invention relates to the reconditioning of steam boilers by reducing the concentrates in the boiler water while the boiler is under steam pressure, thereby effecting a great saving in the idle time of a boiler over the practice of completely blowing down the boiler and then refilling it. Furthermore, by maintaining the boiler under steaming pressure and temperature during the reconditioning, the injurious effects occasioned by cooling down and reheating the boiler resulting in the unequal stresses and strains imposed thereon are obviated.

The present invention constitutes an improvement upon the method disclosed in my prior application Serial No. 300,329, filed October 20, 1939, in that its use in essential respects is not dependent upon an available supply of extraneous steam. While stationary as well as portable boilers may be reconditioned with my present invention, it is particularly valuable for the reconditioning of locomotive boilers. The fact that an available supply of extraneous steam is not essential, renders the use of my invention in connection with locomotive boilers possible at round-houses and stations not equipped with power boilers and under conditions which have heretofore been deemed unsuitable for the accomplishment of the purposes for which my present invention is designed.

Furthermore, the apparatus by which my method may be practiced involves novelty in design and operation which makes possible the reconditioning of boilers in a most efficient and economical manner.

The present practice on some railroads is to clarify or purify the boiler water of the locomotives by reducing the concentrates therein without completely blowing down, washing out and refilling the boiler except at periodic intervals of considerable length. According to this method approximately 600 gallons of the contaminated water will be blown off, whereupon, by means of the locomotive injector, the blown off water will be replaced with water from the tender at a temperature of from 40 to 50° F. Such blowing off and replacing operations will be repeated two or three times in order to produce a satisfactory water condition in the boiler, since each 600 gallon blow-off will customarily reduce the boiler concentrates approximately ten grains. The temperature of the water introduced by the injector is raised by the injector steam to the neighborhood of 160° F., but this is relatively so cold in comparison with the water in the boiler, which at 150 pounds of steam has a temperature

of 365°, that the introduced water sinks rapidly to the bottom of the shell, thereby cooling the shell and imposing excessive strains of contraction and expansion thereon, and also cools the walls of the firebox, thus impairing the combustion of the fuel.

During the successive water blow-offs and replacements in accordance with this method, the locomotive is continuously fired and maintained under a forced draft to heat as rapidly as possible the cold water introduced into the boiler. It has been demonstrated that for each 600 gallons of water change effected in accordance with this method, a coal consumption of approximately 600 pounds is required to heat the water thus introduced. Four blow-offs of 600 gallons each which aggregate approximately one-third the capacity of a modern boiler, requires a coal consumption of approximately 2,400 pounds to restore the water temperature and steam pressure to normal operative condition in the boiler.

In accordance with my present invention, the same reduction of boiler concentrates is effected in a much shorter period of time, the boiler temperature is not reduced sufficiently to produce injurious strains and stresses in the boiler shell, and the fuel required to restore the boiler to normal working water temperature and steam pressure is only approximately fifty per cent. of that at present required in the practice of the method above outline.

Briefly stated, my improved method by which the above mentioned advantageous results are attained involves the same partial blowing down and water replacement operations as are employed in the injector method above described. The blown off water, however, instead of being thrown away, is conserved to the extent that its heat units are transferred to the clean refill water so as to raise the temperature of this water to somewhere in the neighborhood of 180°. The apparatus for thus transferring the heat units is not herein shown on the drawing, as it is of well known character such, for instance, as that shown in my prior Patent No. 2,260,857, issued October 28, 1941. This partially heated refill water is then delivered under pressure to a heater or heat booster such as shown in Fig. 3 of said patent, where the refill water is heated to a temperature of approximately 300° F., by admixing therewith water at high temperature taken from the boiler being conditioned. Assuming that the steam pressure in such boiler is at a normal of 150 pounds, the water delivered from the boiler to the heater for admixture with the refill water

will be at a temperature of approximately 365° F. The ultimate mixture of refill and boiler waters will have an intermediate temperature, depending of course upon the relative proportions of such waters delivered to the heater, but under normal conditions its temperature will approach 300°, which is obviously so much hotter than the 160° water delivered to the boiler by the injector method that no injurious cooling of the boiler shell will result and the water temperature and steam pressure in the boiler will not be unduly lowered. This hot mixture is delivered under pressure to a pump which raises its pressure sufficiently above the pressure existent in the boiler to cause its delivery into the boiler against the boiler pressure. In this manner the boiler is maintained at high temperature and under steam pressure during the reconditioning, so that the unfavorable conditions created by the injector method of reconditioning are obviated, the reconditioning is accomplished in a shorter time and the boiler is restored to normal working temperature and pressure with a fuel consumption of approximately one-half that required by the injector method.

For the purpose of facilitating an understanding of my invention, one form of novel apparatus by which my method may be carried out is shown on the accompanying drawing, referring to which,

Fig. 1 is a schematic view of the apparatus; and

Fig. 2 is a horizontal sectional view on the line 2--2 of Fig. 1.

The drawing exemplifies an installation of my novel apparatus along side a track upon which the locomotive to be reconditioned stands. Usually, although not necessarily, the installation will be made in a roundhouse and the apparatus located between two adjacent locomotive stalls, so that it may be connected to and employed for conditioning a boiler of a locomotive standing in either stall.

A roundhouse adapted for boiler washing and refilling is usually equipped, as illustrated in Fig. 1, with a blow-off line 5 through which the blown off products are delivered to suitable heat conserving equipment, such, for instance, as that illustrated in my prior patent above referred to. A customary installation also includes the refill line 6 by which refill water which has been partially heated by the blown off products is conveyed to the locomotives for refilling purposes. Those roundhouses which have repair shops including power operated machines associated with them are usually provided also with a steam supply line 7 which receives its steam from the power boilers. Such a steam supply is not essential to the practicing of my improved method or the operation of my novel apparatus, but in installations where such steam is available it may be connected to my apparatus as a means of heating refill water for completely refilling a locomotive which has been completely blown down and washed out.

The refill line is connected by a drop 8 with a heater or heat booster 9 of the type disclosed in my said prior patent, which comprises a Venturi tube 11 into which the refill water from the pipe 6 is delivered by a nozzle 12. The supply of refill water so delivered should be subject to control and regulation, and, in order to obviate the necessity of accurate adjustment or setting of a single control valve, I prefer to interpose between the pipe 6 and the heater 9 a plurality of, in the present instance three, smaller branch or

shunt pipes aggregating in cross-sectional area the area of pipe 8. Each of these branch pipes is equipped with a control valve 14 which will always be either fully open or fully closed. In this manner the quantity of refill water delivered to the heater is regulated by the number of valves opened, thereby obviating the danger of imperfect control resulting from the careless setting of a single control valve. The pressure of the refill water entering the heater may be ascertained from a pressure gauge 15.

A pipe 16 communicating with the chamber of the heater surrounding the nozzle 12, is provided at its outer end with a flexible conduit, herein illustrated as comprising a plurality of pipe sections 17 and ball connections 18 affording the requisite flexibility. A threaded connecting element 19 affords provision for connection to a boiler shell, such connection being usually made through the blow-off cock opening into the boiler located at a low level in the boiler leg 21, as illustrated. A conventional boiler 22, shown in dotted lines, includes a typical steam dome 23. Pipe 16 is provided with a shut-off valve 24 and a similar valve 25 is preferably located in the flexible connection near the point of attachment to the boiler.

From the heater 9 a pipe 26 leads to the intake of a pressure pump 27 driven by a motor 28. For convenience, pipe 26 is provided with a thermometer 29. The pump is adapted to raise the pressure of the fluid handled about 25 pounds, and the fluid is delivered through pipe 21 and suitable flexible connections to the boiler, preferably through the dome 23.

The first step in reconditioning a boiler in accordance with my method is to blow off approximately 600 gallons of contaminated water. This water is delivered into the boiler washing and refilling system where its heat is utilized to heat fresh refilling water in a well-known manner. In order to blow off this water, the connection 19 is attached to the boiler shell. Valve 24 is closed, valve 32 in branch pipe 33 is opened, valve 34 at the suction side of the pump is closed, and valve 35 in a pipe 36 leading from a heater 9 to the blow-off line 5 is opened. Upon opening valve 25, the contaminated boiler water is blown through connections 17, pipe 33, pipe 26, the lower portion of heater 9, pipe 36, and blow-off line 5 to the heat conserving apparatus of the boiler washing and refilling system. When the boiler gauge glass shows that the desired amount of contaminated water has been blown off, valves 35 and 32 are closed, valve 34 is opened, and one or more of valves 14 is opened. This permits a delivery of clean refill water from the refill line 6 to the heater, where it is discharged by the nozzle 12 into the venturi 11 and thence to the intake side of the pump. This refill water will be at a temperature ranging between 160 and 180° F., and under an approximate pressure of 200 pounds. The valve 24 is then opened permitting the delivery of water from the boiler to the upper chamber of the heater 9, from whence it is drawn through the venturi 11 by the jet issuing from nozzle 12, so that this water is thoroughly mixed with the refill water to produce a resultant mixture of high temperature. While the proportions of refill water and blow-off water may be varied by manipulation of valves 14 and 24, satisfactory results under normal conditions are obtained by a delivery to the heater of refilling water and blow-off water in substantially the proportions of one to two, that

is, if valves 14 permit a flow of refill water at a rate of approximately 40 gallons per minute, the blow-off water delivered to the heater from the locomotive will be approximately 80 gallons per minute. If the pressure of the boiler is in the neighborhood of 150 pounds, the water blown off will have a temperature of approximately 365° F. The resultant mixture of one gallon of refill water at a temperature of 180° with two gallons of blow-off water at a temperature of 365° will have a temperature of approximately 300° F., and be delivered to the suction side of the pump, under a pressure somewhat below the boiler pressure but sufficient to prevent steam flashing of the superheated mixture.

The pump is adapted to raise the pressure of the heated mixture of fresh and boiler waters to a point above boiler pressure, so that it will be delivered through the line 31 into the boiler at any preferred point, such, for instance, as through the steam dome as illustrated on the drawing. When the water level in the boiler has been restored to normal by the introduction in the manner described of approximately 600 gallons of refill water, the valves 14, 24, and 34 are closed and valves 32 and 35 are opened to permit another blow-off from the boiler. When the desired amount has been blown off, this amount is again replaced with refilling water in the manner described and such alternate blowing off and replacing operations may be continued until the desired reduction in concentrates of the boiler water has been attained. In practice, three or four partial blow-downs are sufficient to produce a satisfactory water condition in the boiler.

While I have described the blow-down and water replacement operations as being performed in alternation by the apparatus described, it should be understood that if the roundhouse is equipped with my apparatus on each side of the locomotive, the blow-down may be performed on one side of the locomotive by one apparatus while the water replacement or refill is simultaneously performed by another apparatus on the other side of the locomotive. Such practice obviously results in a considerable saving of time over the alternate blowing down and refilling, and the ultimate results within the boiler are the same in both instances.

In addition to its function of reconditioning boilers by a succession of partial blow-downs and refills, my apparatus is also adapted for completely blowing off and refilling boilers with hot water where the roundhouse is equipped with the live steam pipe 7 and sufficient steam for heating purposes is made available by the power boilers. In such instances a pipe 37 connects the steam line 7 with the pipe 16 leading to the heater, and a shut-off valve 38 is interposed in pipe 37. If a boiler is to be completely blown down,

the partial blow-down procedure is continued until complete blow-off has been accomplished. In such instances, the boiler is usually washed out and perhaps subjected to repair work, and upon refilling the partially heated refill water, instead of being further heated by blow-off water from the boiler, is heated by steam from the line 7. To accomplish this result, valve 24 is closed and valve 38 is opened, whereupon the refill operation 10 will proceed in the manner described in detail in my prior Patent No. 2,260,857.

To obviate possible air locking or steam locking of the pump 27 resulting from careless or improper manipulation of the apparatus, I have 15 provided a relief pipe 39 extending from the pump casing to the pipe 36, and pipe 39 is equipped with a shut-off valve 41 which, in the event of such locking of the pump, may be opened to relieve the lock.

20 Vertical supporting posts are customarily located between the pits or stalls in a roundhouse. One of such posts indicated by reference character 42 is shown in Fig. 2, from which it will be apparent that the design of my apparatus is such that the post does not interfere with its installation or operation. To avoid confusion, the post 25 is not shown in Fig. 1.

From the foregoing it will be manifest that by my improved method and apparatus a boiler 30 may be reconditioned by reducing the boiler water concentrates without subjecting the boiler shell to injurious stresses and strains such as are incident to the introduction of cold or cool water into the boiler. The boiler water itself is used as the heating medium to raise the temperature 35 of the refilling water to a point where no injury to the boiler shell will result from its introduction, and the pressure requisite for the introduction of the refill water against the boiler pressure is provided by a pump capable of increasing the pressure the requisite amount over that existing at its intake.

The structural details illustrated and described 40 may obviously be varied within wide limits without exceeding the scope of my invention as 45 defined in the following claim.

I claim:

The method of reconditioning steam boilers 50 while under steam pressure, which consists in blowing off a portion of the contaminated boiler water, introducing into a heater refill water adapted to replace said drawn off water, introducing into said heater water from the boiler whereby to heat the refill water to a temperature suitable for introduction into the boiler, then raising the pressure of said heated water to a point above the pressure existent in the boiler and delivering said heated water into the boiler.

FRANK W. MILLER.
